UNITED STATES PATENT OFFICE.

CLIFFORD RICHARD VAN DUSEN, OF TORONTO, ONTARIO, CANADA.

SANDING DEVICE.

Application filed October 6, 1919. Serial No. 328,809.

To all whom it may concern:

Be it known that I, CLIFFORD RICHARD VAN DUSEN, a subject of the King of Great Britain, and resident of 310 Clendenan Ave., 5 in the city of Toronto, county of York, Province of Ontario, in the Dominion of Canada, have invented certain new and useful Improvements in Sanding Devices, of which the following is a specification.

10 The invention relates to improvements in sanding devices as described in the present specification and shown in the accompanying drawings that form a part of same.

The invention consists essentially of the 15 novel features of construction whereby sand or other similar material is delivered to the road surface directly in advance of the vehicle wheels.

The objects of the invention are to eliminate skidding of the vehicle and thus prevent accidents, to provide a sanding device which will be instantaneous in its action, to provide a device which will be neat and attractive in appearance and which may be 25 adapted to any form of vehicle and generally to provide a sanding device which will be inexpensive of construction, efficient in operation and durable.

In the drawings, Figure 1 is a side view of 30 a portion of a car with the device in position thereon, a portion of said car being broken away to disclose the operating means.

Figure 2 is a plan view from the under side of the car.

Figure 3 is an enlarged longitudinal sectional view through the hopper and delivery spout and valve taken on the line A—A of Figure 4.

Figure 4 is a plan view of the inner face 40 of the hopper bottom, said bottom being broken away to show the relation of the valve or shutter thereto.

Figure 5 is a side elevation showing a modified form of hopper for use on trucks 45 or vehicles not provided with a running board.

Like numerals of reference indicate corresponding parts in the various figures.

Referring to the drawings 1 and 2 are 50 sand storage receptacles, shown in drawings as being in the form of elongated tapered boxes secured to the under sides of the running boards 3 of the vehicle but it must be understood that these storage receptacles

may be located in any desired position and 55 provided with suitable means for delivering the sand to the delivery hoppers.

4 and 5 are hoppers or delivery boxes secured to the under sides of the running board directly in advance of the driving 60 wheels of the vehicle, said hoppers in the drawings being shown as forming continuations of the storage receptacles 1 and 2 respectively but in cases where it is desirable to locate said storage receptacles elsewhere 65 suitable means may be provided for delivering sand from said receptacles to said hoppers.

The bottoms of the hoppers 4 and 5 are sloped downwardly towards the delivery 70 ends, so as to insure an adequate supply of sand at said delivery end, and are provided with a series of openings 6 thereacross through which the sand is adapted to flow.

7 are spouts with which each of the hoppers is provided at its delivery end, the sides of said spouts adjacent to the wheels being shaped to substantially follow the contour of the wheels for the greater portion of their 80 length and terminate in outwardly curving lips 8 while the opposite walls slope downwardly in a straight line towards the rear walls and terminate slightly short of the lips 8 leaving a narrow slit 9 in each spout 85 through which the sand passes from the hopper above to the road surface directly in advance of the wheels.

10 are plates supported in any desired manner slightly below the bottoms of the 90 hoppers and extending from the extreme outer ends of said hoppers to a point considerably in advance of the openings 6 in said bottoms and being provided with a series of openings 11 registering with said 95 openings 6 but being of considerably greater dimensions than said openings 6.

12 are plates or valves slidably arranged between the bottom of the hoppers respectively and the corresponding plates 10, said 100 valves being adapted to project past the front ends of the plates 10 and being provided with downwardly projecting lugs 13 to the front sides of which are secured hooks 14.

15 are springs secured to the lugs 13 from the valves 12 and to lugs 16 from the plates 10 and exerting a pull on said valves to

hold them normally to the rear ends of said hoppers to prevent the escape of the sand from said hoppers.

17 are cables secured to the hooks 14 of 5 the lugs 13 and operating through brackets 18 secured to the bottoms of the hoppers and being secured together as at 19 substantially centrally of the vehicle body and extending in a single cable or rod 20 through the car 10 body and terminating in any convenient location, preferably in close proximity to the steering rod. The end of the cable or rod 20 may of course be provided with any convenient form of handle with which to 15 exert a pull on same for drawing the valves forwardly to permit of the sand passing through the openings in the hopper bottoms and the corresponding plates 10.

The cable or rod 20 may also be supported at intervals by brackets 21 or by 20 other desired means to hold same to its proper position.

If desirable curved tubular members 22 25 may be rigidly supported within the brackets 18 for the purpose of loosely accommodating the cables 17 to reduce to a minimum the wear on said cables.

23 are discs rigidly secured to the cables 17 a distance to the rear of the tubes 22 30 slightly greater than the distance between the outer ends of the hoppers and the front edges of the sand openings 11 in the plates 10, said discs being of greater dimensions than the openings in said tubes and forming 35 stops to limit the opening movement of said valves.

24 is an apron shown in dotted lines as 40 being suspended from the outer edge of the running board to conceal the storage receptacle.

In Figure 5 a modified form of storage receptacle and hopper is shown, this construction being adapted particularly for use on trucks and other forms of vehicles not 45 provided with running boards from which to suspend the various parts.

The storage receptacles 25 are preferably 50 of conical formation and are supported slightly in advance of the wheels of the vehicle. The bottoms of said receptacles are provided with screens 26 thereacross which tend to relieve the hoppers of the weight of the sand but which at the same time permit of an adequate supply of sand passing into 55 the hoppers 27 which are located therebelow, the construction of said hoppers being similar to that of the hoppers 1 and 2 as described hereinbefore.

The valves in this form of construction

are preferably operated by means of a toggle mechanism consisting of a transverse rod 27 rotatably mounted in bearings in brackets 28 supported from the vehicle frame, crank levers 29 connecting the ends of said rod with the adjacent valve and a rod 30 rigidly secured centrally of said rod and projecting downwardly therefrom and having secured to the lower end thereof a rod or cable 31 which projects through the car body and is provided with a handle or other operating means located within convenient reach of the operator.

Owing to the shape of the storage receptacles the sand will flow therefrom into the hoppers as fast as the sand already in said 75 hoppers is released therefrom and in the use of the invention it is only necessary when desirable to provide a gripping surface to pull on the handle or other means with which the cable or rod 20 is provided and this has the effect of drawing the valves forwardly and permits of the sand falling through the openings in the hopper bottoms and the plates 10 into the spouts 7 which deflect it on to the roadway directly in 85 front of the driving wheels. As soon as the cable 20 is released the springs 15 force the valves to their normal positions over the openings 11 and thus effectually prevent the escape of sand.

While I have thus described the preferred construction, combination and arrangement of parts which constitute the present invention, it is obvious that others skilled in the arts to which this appertains, may make 95 various changes without departing from the spirit and scope of the invention as contained in the claim for novelty following.

What I claim is:—

The combination in a vehicle, of a pair 100 of elongated storage receptacles secured to the under sides of the running boards respectively, said receptacles increasing in depth to their rear ends and terminating in substantially spout shaped hoppers, the top 105 walls of said hoppers and the bottom walls of said receptacles being spaced and being provided with sand outlets, valves interposed between said hoppers and said receptacles respectively and spring held to their closed 110 positions, and means for operating said valves.

Signed at the city of Toronto, Province of Ontario, this 2nd day of October, 1919.

CLIFFORD RICHARD VAN DUSEN.
